UNITED STATES PATENT OFFICE.

EMIL WEINHEIM, OF NEW YORK, N. Y.

APPARATUS FOR IMPREGNATING FRAGILE FABRIC.

1,306,650.

Specification of Letters Patent. Patented June 10, 1919.

Application filed July 10, 1918. Serial No. 244,137.

To all whom it may concern:

Be it known that I, EMIL WEINHEIM, a citizen of the United States, and a resident of New York city, county and State of New York, have invented certain new and useful Improvements in Apparatus for Impregnating Fragile Fabric, set forth in the following specification.

This invention relates to a process and apparatus for impregnating a strip of fragile body fabric with a character converting dope, as a continuous process. By "fragile" is meant that the body fabric is of such a character as to be difficult of manipulation without material distortion, such as is the case with cotton batting or a batt made up part cotton and part other vegetable fibers.

In my co-pending application, Serial Number 235,445, filed May 20, 1918, for the manufacture of hide leather, I have described one process and apparatus employing endless apron protectors for employment in impregnating a fragile fabric. In accordance with the present invention it is an object to effect the impregnation and completion of such a body fabric without the employment of endless aprons. One feature in common between this application and my above cited application is, however, broadly a downward feeding of the strip of fragile body fabric.

In furthering the broad objective of this invention I propose in combination three principal steps,—first, a downward feed of the strip of fragile body fabric so that gravitation will have no tendency to disrupt the same; second, the local heating of a bath of dope with a strip of the fabric passing downward through it; and third, subjecting the saturated fabric to a laterally applied continuous rolling pressure combined with a surface chilling and congealing action.

The local heating renders the dope more fluid, while the chilling in combination with rolling pressure forms a congealed section on the opposite sides of the treated fabric which adds greatly to the strength of the body fabric and prevents undue adherence of the treated fabric to the compression rollers.

The above and further features and details of my invention will better be understood by reference to the illustrative embodiment shown and described merely for purposes of

illustration in this application, of which the accompanying drawings form a part, like characters in the two figures designating corresponding parts. In the drawings—

Figure 1 is a diagrammatic representation of preferred apparatus, shown partly in elevation and partly in vertical section, for the embodiment and practice of my invention; and

Fig. 2 is a horizontal section, partly in plan, taken along line II—II of Fig. 1.

A power driven endless carrier 1, which may be a canvas apron, and which preferably passes over a steam-heater 2, serves to deliver a strip 3 of the desired body fabric to be employed, preferably directly from a batting machine. The purpose of the heater 2 is to expel all moisture immediately before the strip 3 enters the impregnating dope tank. This dope tank is preferably double-walled, containing the steam heating coils 5 within an outer covering 6, which may be wholly or in part non-heat conducting material. Arranged centrally and suitably journaled in the upper part of the tank 4 is a carrier drum 7 having fabric-gripping cross slats 8 in elemental positions on its periphery. This drum 7 is preferably rotatably driven at a peripheral speed equaling the delivery speed of the strip 3 by the apron 1.

A charge of dope 9 is preferably maintained at constant level approximately as indicated in the drawing by a suitable replenishing feed. It is preferred that this dope be such as has been described in my Patent No. 1,263,171, granted April 16, 1918, a process of forming leather substitutes, although this dope is preferably for manufacture of a leather substitute. I appreciate, however, that my process and apparatus are well adapted for the impregnating of any fragile body fabric with any kind of character converting dope known to the art, including rubber compounds, the principal purpose of the invention being to make possible a direct impregnation of such a fragile body fabric as a continuous process without injury to such body fabric.

After overshooting or passing over the feed drum 7 the continuously fed strip 3 of body fabric contacts with the dope 9, maintained as fluid as possible by the steam-

heated tank 4. The drum 7 serves practically to permit the strip of fabric to fall without applying any strain upon it. Almost immediately upon engaging the impregnating dope 9 it has a support by a second drum 10, driven at a peripheral speed to correspond to the progress of the strip 3 and preferably completely bathed in the dope 9 and steam-heated. This strip of fabric 3 merely laps about this drum and progresses downwardly through the tank 4, principally by gravity, although the drum 10 may have a tendency to aid this downward progress rather than to hinder it. The tank 4 is merely trough-like, having a bottom exit opening 11, directly above a pair of laterally positioned compression rollers 13 and 14, preferably adjusted as to separation in any suitable manner, as by the micrometer adjuster 15. These compression rollers are preferably similar in construction to steam-heatable calender or compression rollers, but instead of being steam-heated are supplied with a continuous flow of chilling fluid such as cold water or brine. These rollers, as has been stated, are compression rollers, in contra-distinction to the drum 10, the operating cylindrical surface of which may be sheet metal such as copper or zinc. Within the bottom exit opening 11 of the tank 4 and coöperating as a slidably extension closure with the side walls 16 and 17 of the tank 4 are a pair of saddles 18 and 19, preferably formed of bronze when the rollers 13 and 14 are made of steel, and having a configuration exactly fitting the cylindrical surfaces of the rollers 13 and 14 forming, as it were, end partitions serving to confine the dope 9. The direction of rotation of the compression rollers 13 and 14 is indicated by the arrows in Fig. 1, and the complete sealing except to permit the exit of the impregnated and compressed part 20 of the strip of fabric 3 is provided by a pair of hinged scrapers 21 for the roller 13 and 22 for the roller 14. These scrapers preferably extend elementally of the rollers the complete distance between the saddles 18 and 19, and may conveniently be hinged as indicated by the hinges 23 and 24 from the bottom of the dope tank 4. The small arrows *a* in Fig. 1 indicate how the pinching action between the compression rollers 13 and 14 cause an upward flow of dope against either the scrapers 21 or 22, so that the strip 20 of fabric which passes down between the rollers 13 and 14 contains not an over-, but merely a complete impregnation with both surfaces congealed by the chilling action of the cold rollers 13 and 14. To insure, however, that there should be no continued multiplication of any small particles or residue of dope adhering to the rollers 13 and 14 after freeing the strip 20, a pair of suitably hinged spring-pressed

scrapers 31 and 32 are arranged to scrape the surfaces of the rollers 13 and 14.

The strip 20 of fabric passing down between the compression rollers is no longer fragile and according to the dope employed may be or may not be completely finished. As a rule, however, nothing further is required except curing, which may be accomplished in any well-known manner.

What is claimed and what is desired to be secured by United States Letters Patent is:—

1. The continuous process of impregnating a strip of fragile non-self-sustaining body-fabric with a character converting dope comprising imparting a continuous substantially downward movement through a directly contacting bath of suitable dope having the quality of being relatively more fluid when heated; subjecting said bath of dope and said strip when passing down through said bath to the influence of heat; and subjecting said strip immediately upon its exit from said bath to horizontally applied pressure and surface chilling.

2. Apparatus for impregnating by continuous process a strip of fragile non-self-sustaining body-fabric, comprising a dope-tank having an exit opening at the bottom for said strip; a pair of laterally positioned cooling compression rollers forming part of a bottom closure to confine a suitable dope and adapted to pass downwardly therebetween said strip of body-fabric; and means for imparting a downward continuous feeding to said strip through said dope-tank into direct contact with said cooling compression rollers.

3. Apparatus for impregnating by continuous process a strip of fragile body-fabric, comprising a dope-tank having an exit opening at the bottom for said strip; a pair of laterally positioned cooling compression rollers forming part of a bottom closure to confine a suitable dope and adapted to pass downwardly therebetween said strip of body-fabric; and means for imparting a downward continuous feeding to said strip through said dope-tank, said means having provisions for heating said strip locally in its passage through said tank.

4. Apparatus for impregnating by a continuous process a strip of fragile body-fabric comprising a dope tank; a heated rotatably driven drum in said tank having one-sided contact with a downwardly feeding lap of said strip; and a pair of laterally positioned rotatably driven cooling compression rollers for directly manipulating said strip during its continued downward progress.

5. Apparatus for impregnating by a continuous process a strip of fragile non-self-sustaining fabric (such as a fibrous batting), comprising a dope tank having a bottom opening for said strip; means for guid-

ing said strip downwardly through the dope space of said tank so that where necessary the direction of movement overcomes gravity otherwise tending to strain said strip; and means for imparting body strength to said strip upon leaving said opening comprising means for surface

chilling, for exerting lateral compression upon said strip and for drawing said strip away from said tank.

In testimony whereof I have signed my name to this specification, this 29th day of May, 1918.
